(57) **CLAIM**

The ornamental design for an aircraft nose, as shown and described.

DESCRIPTION

FIG. 1 is a perspective view taken from a top, front, left side of an aircraft nose according to our new design shown on an aircraft shown in broken lines;

FIG. 2 is a left elevation view thereof;

FIG. 3 is a right elevation view thereof;

FIG. 4 is a top plan view thereof;

FIG. 5 is a bottom plan view thereof; and,

FIG. 6 is a front elevation view thereof.

Throughout the Figures, broken lines showing environment or structure are for illustrative purposes only and form no part of the claimed design. Dash-dot broken lines represent the boundary between claimed and unclaimed areas and form no part of the claimed design.

1 Claim, 6 Drawing Sheets
